UNITED STATES PATENT OFFICE.

GEORGES L. E. PÉTORIN, OF SAN FRANCISCO, CALIFORNIA.

LOCK.

SPECIFICATION forming part of Letters Patent No. 605,337, dated June 7, 1898.

Application filed March 10, 1898. Serial No. 673,294. (No model.)

To all whom it may concern:

Be it known that I, GEORGES L. E. PÉTORIN, of San Francisco, in the county of San Francisco and State of California, have invented 5 a new and Improved Lock, of which the following is a full, clear, and exact description.

My invention relates to an improvement in locks of that kind which are adapted for use in connection with doors; and it consists of 10 certain novel features of construction, which will be hereinafter described and claimed.

Reference is to be had to the accompanying drawings, forming a part of this specification, in which similar characters of reference indicate 15 corresponding parts in all the views.

Figure 1 is a plan view of my lock with one side of the casing removed. Fig. 2 is a section taken upon the line 2 2 of Fig. 1. Fig. 3 is a section taken upon the line 3 3 of Fig. 1. 20 Fig. 4 is a section taken upon the line 4 4 of Fig. 1 with the locking-lever in one position. Fig. 5 is a section taken upon the same line with the locking-lever in another position, and Fig. 6 is a perspective view showing the 25 bit of the key.

As shown in the drawings, this lock is mounted in a rectangular casing A, of the usual style, apertured at one side to receive the end of the locking-bolt B. The casing 30 is closed by a removable cover consisting of a plate A', secured in place by screws or any other suitable means. The form of the casing is, however, immaterial, as the lock may be inclosed in any suitable casing.

The casing is provided with a securing-staple H, adapted to engage the inner end of the bolt B and guide it in its movements. The bolt B is provided upon one side with a series 35 of projections forming between them notches f, adapted to be engaged by a pin upon the locking-lever, hereinafter described, so as to prevent the bolt from being thrown in either direction. Upon the opposite edge of the bolt are projections forming semicircular notches 40 f', adapted to be engaged by the bit of the key G to throw the bolt. As herein shown, the lock is constructed with three locking-notches upon one side and two notches for the engagement of the key upon the other, 45 this construction being that adapted for a double-throw bolt—that is, a bolt which may be given two throwing movements by a double

revolution of the key. The number of these notches will be decided by the number of turning movements of the key desired. 55

At one side of the bolt and extending substantially perpendicular to the direction of the bolt are two pivot-flanges C, which near the end farthest from the bolt are provided with undercut notches C', which extend downward from the side of the flange and then parallel with the side and outward away from the bolt, as clearly shown in Fig. 3, and upon the ends of these flanges nearest to the bolt are inwardly-projecting lugs or stops C². A locking-lever is pivoted upon the flanges C and is adapted to engage the bolt to prevent its being thrown. As herein shown, this lever is constructed as a yoke D, the two arms D' of which are at such distance apart that they fit snugly between the flanges C. The outer ends of the arms D' are provided with pins d, adapted to enter the notches C' in the pivot-flanges, and upon which pins the yoke or locking-lever pivots. That portion of the arms D' 75 lying alongside the the pivot-flanges is made somewhat broader than the remainder. This forms a shoulder D², which lies just next the lugs C² and prevents the yoke from being moved endwise a sufficient distance to disengage its pivots from the slots C'. With this construction it is evident that the yoke-pivots may be put in place in the slots C' when the other end of the yoke is raised, this being easy of accomplishment when the cover A' is removed. Unless the outer or swinging end of the lever can be raised the locking-lever cannot be removed from its place. At the point where the two arms of the yoke meet said lever is provided with a central body E, extending in 80 each direction from said point of union. Upon the outer end of this central body is fixed a spring E', adapted to engage the plate or cover A', and thus to hold this end of the yoke down in place, but also to permit the yoke to be raised slightly when force is applied thereto. At the outer end of this central body E is a pin E², extending downwardly and so located as to enter the notches f, formed in one edge of the bolt B. While the pin E² is within one of the notches f, the bolt B cannot be thrown in either direction. The opposite end of the central body E is in line with the keyhole and extends to a point near 85 90 95 100

the same. Said body is preferably provided with downwardly-extending pins *e*, located near one end thereof.

The key *G*, which is used in connection with the lock, is shown in Fig. 6. The bit of this key is provided with a notch *G*², close to the stem thereof, and with a second notch *G*³, located nearer the other end of the bit. Between these two notches the key is provided with a rib *G'* upon each side thereof, making this section of the key of considerably greater thickness than the remainder. The corners of the rib are beveled, forming inclines which are adapted to engage the under surface of the inner portion of the central body *E* of the locking-lever. As the key is turned after insertion within the lock these inclines, engaging the under surface of the yoke or lever, will raise the same slightly, so as to free the bolt from the pin *E*², thus permitting the bolt to be thrown. This engagement of the key with the yoke or locking-lever is before the key engages the bolt. The key engaging the bolt will then throw the bolt, and as it passes from beneath the yoke will allow the bolt to drop into place, the pin *E*² entering another one of the notches *f* and holding the bolt until the yoke is again raised. The bolt is thus positively held in any and all positions, so that it cannot be thrown except when the yoke is raised. The pins *e* upon the under surface of the yoke at the end nearest the key are intended to engage the bit of any other than the proper key when the latter is inserted in the lock. These pins are placed at such a distance apart that they will permit the bit of an ordinary key to drop between them, and thus hold the key against removal. The casing *A* may be provided with ribs or projections *I* to prevent the turning of a key which does not have notches in the proper place.

As shown by dotted lines in Fig. 1, keyholes *a* *a'* may be provided in each side of the casing, said keyholes, if desired, being at right angles to each other. That part of the keyhole which receives the stem may also be surrounded by an internal flange *a*², which will support the end of the key.

Having thus described my invention, I claim as new and desire to secure by Letters Patent—

1. A lock, comprising a sliding bolt, and a pivoted and spring-pressed yoke-shaped locking-lever provided with a central body, one portion of which has an interlocking engagement with the bolt, and the other portion extending to within a short distance of the keyhole, substantially as described.

2. A lock, comprising a sliding bolt, and a pivoted and spring-pressed yoke-shaped locking-lever provided with a central body, one portion of which has an interlocking engagement with the bolt and the other portion extending to within a short distance of the keyhole and provided with pins on one face, substantially as and for the purpose set forth.

3. A lock, comprising a casing, a sliding bolt provided with notches on opposite sides, a yoke-shape lever having its members loosely pivoted in supports on the casing and provided with a central body, one portion of which is provided with a pin engaging one set of notches of the bolt, the other portion of the body extending to within a short distance of the keyhole and provided on one face with pins, and a spring between the said body and casing, substantially as described.

4. A lock, comprising a bolt, having locking projections, a yoke-shaped locking-lever pivoted to swing upon pivots substantially parallel to the bolt, and adapted to engage at its free end said locking projections upon the bolt, a central arm or body projecting near the keyhole and adapted to be engaged by the key before the latter engages the bolt to throw it, and a spring adapted to normally hold said lever in locking engagement with the bolt, in combination with a key having inclines upon the edges of its bit, adapted as the key is rotated, to engage said lever and raise it free of the bolt before engaging the bolt to throw it, substantially as described.

5. A lock, comprising a bolt having locking projections thereon, a yoke-shaped locking-lever pivoted to swing upon pivots substantially parallel to the bolt and adapted to engage at its free end said locking projections upon the bolt, a central body projecting from the yoke-shaped lever near the keyhole and adapted to be engaged by the key before the latter engages the bolt to throw it, said central body having downwardly-projecting pins disposed across the same, and a spring adapted to normally hold said lever in locking engagement with the bolt, in combination with a key having a blade cross-shaped or formed with a central cross-web, the end corners of said cross-web being inclined and adapted to engage said lever to swing it free of the bolt before engaging the bolt to throw it, substantially as described.

6. A lock, comprising a bolt provided with means for engagement of a locking-lever and a key therewith, pivot-flanges at one side of the bolt extending substantially at right angles thereto, said flanges having each an undercut notch, a yoke-shaped lever having its arms adapted to fit within said flanges and having pins at the ends of said arms adapted to enter the notches in said flanges, the other end of said lever being adapted to engage and lock the bolt, and the lever being adapted to be engaged by the key and swung upon its pivot to free the bolt, substantially as described.

7. A lock, comprising a bolt provided with means for engagement of a locking-lever and a key therewith, pivot-flanges at one side of the bolt extending substantially at right angles thereto, said flanges having each an undercut notch, a yoke-shaped lever having its arms adapted to fit within said flanges and having pins at the ends of said arms adapted

to enter the notches in said flanges, the other end of said lever being adapted to engage and lock the bolt, and the lever being adapted to be engaged by the key and swung upon its pivot to free the bolt, the pivot-flanges having retaining-lugs at the end opposite the pivot-notch, and the yoke having shoulders

engaging said lugs, to prevent longitudinal movement of the yoke, substantially as described.
